UNITED STATES PATENT OFFICE.

JESSE C. COOK, OF JEFFERSONVILLE, INDIANA, ASSIGNOR TO AMERICAN CREOSOTING COMPANY, OF LOUISVILLE, KENTUCKY, A CORPORATION OF DELAWARE.

HEATING SYSTEM FOR STORAGE TANKS.

Application filed December 23, 1927. Serial No. 242,258.

This invention relates to heating systems for storage tanks and particularly to systems for use with tanks in which viscous liquids such as creosote, tar or the like are stored.

Storage tanks for creosote, tar and like liquids which are viscous at ordinary atmospheric temperatures, and which become solid, and in some cases deposit out crystals at lower temperatures, must receive heat from an external source, to bring the contents of the tank back to a liquid state. One method of supplying this heat is to have coils built up of pipe and fittings placed in the tank with connections through the shell of the tank to introduce steam into the coils. To prevent damage to the coils from freezing when they are not in use, drainage must be provided so that all condensed steam may flow out. With some systems the coil designs have required a considerable elevation of portions of the coils to provide the necessary drainage. Systems of this type are open to the serious objection that the space below the coils heats very slowly, and the solid and crystalline material which forms at low temperatures settles out into this poorly heated space.

The amount of material in storage varies from time to time but the tanks are entirely emptied only at relatively long intervals. If a leak develops in the coils, condensed steam will mix with the contents of the tank, and such admixtures are usually very undesirable. It is therefore a distinct advantage to have more than one heating system in the tank, but the duplication of known systems would aggravate the difficulties experienced in heating the material at the base of the tank.

An object of the invention is to provide an efficient heating system which may be positioned very close to the bottom of the tank. A further object is to provide a heating system composed of two independent heating units, the construction being such that both heating systems cover the entire tank bottom, and are arranged in the same plane.

These and other objects of the invention will be apparent from the following specification, when taken with the accompanying drawings, in which

Fig. 1 is a plan view of the heating system as arranged in the bottom of a tank,

Fig. 2 is a fragmentary vertical section through the bottom of the tank, the heating system being shown in elevation,

Fig. 3 is a similar fragmentary vertical section taken on line 3-3 of Fig. 2. 55

Fig. 4 is a fragmentary vertical section showing the connection of the heating pipes to the headers,

Fig. 5 is a vertical section taken at right angles to Fig. 4, i. e., in the plane of the steam header and return header, 60

Fig. 6 is a vertical section through one of the double heating pipes, and

Figs. 7 and 8 show other arrangements for carrying the return headers through the shell of the tank. 65

In the drawings, the numeral 1 indicates the shell of a vertically arranged cylindrical tank in which the heating system is arranged. 70

The heating system is made up of two independent units of similar design, either one of which may be employed to liquify the contents of the tank. The steam headers A, A' of the two systems are preferably parallel to each other, and, as shown in Fig. 2, are arranged at the same level. The cold steam or water return headers B, B' are arranged in the vertical planes of, and below the respective steam headers. The two headers of the respective units are made up from a series of eccentric or double passage cross fittings 2 and short sections 3 of pipe, the fittings and pipe being provided with suitable right and left hand threads to permit the assembly of the header system. As shown in Fig. 5, each duplex cross 2 has an upper passage 4 and a lower passage 5, which passages extend through the cross and cooperate with pipe sections 3 to form the continuous inlet and outlet headers. A chamber 6 extends below the upper passage 4 and is provided with threaded openings for receiving steam pipes 7 which extend in opposite directions and at right angles to the plane of the headers. 85

Steam pipes 7 are located within, and their open ends terminate short of the outer closed ends of return pipes 8 which are threaded into the walls of the chamber 9 of the cross. Return flow chamber 9 surrounds the inlet chamber 6 and communicates with the outlet passage 5 of the return header system. To center the steam inlet pipes 7 within the return pipes 8 of the heater system, the pipes 7 are provided with a series of legs or supports 10. The supports 10 permit water of condensation to flow freely to the return header, and rapid heating may therefore be obtained 100

as the major portions of both the inner and outer pipes of each heating circuit are in contact with the steam.

For convenience in identifying the parts of the two units associated with headers A, B and A', B' respectively, the exponential numbers are applied to the elements of the system having headers A', B'.

It will be noted that the eccentric crosses 10 2 are of such size that the heating pipes of one unit may pass between the upper and lower connecting pipes of the headers of the other unit. This permits the placing of both sets of heating pipes at the same level, as shown 15 in Fig. 2.

The steam inlet pipes 11, 11' enter the shell of the tank approximately at right angles to, and opposite the center of the headers A, A'. Each inlet pipe delivers steam into a cross 20 pipe, 12, 12', respectively, from which steam is passed to spaced points in the headers by a series of feed pipes 13, 13', respectively. The several pipes forming the steam inlet system are arranged at levels above the headers and 25 are supported upon suitable brackets, such as angle irons 14 mounted upon blocks or plates 15.

The steam inlet pipes are preferably arranged to drain towards the headers to remove water of condensation when the system is put out of operation. The supports for the heating pipes 7, 8 may conveniently take the form of structural bars 16 carried by wooden blocks 15. The heating pipes 7, 8, 35 and the outlet headers may be given a slight slope to promote drainage, by appropriate variation in the thickness of blocks 15, or the pipes may be placed in a horizontal plane, as the method of assembly avoids the formation 40 of pockets in which water of condensation may collect.

In one installation, the groups of heating pipes 8, 8' at each side of the headers were given a slope of one-quarter inch in fourteen 45 feet, and the outflow pipes 7, 7' were arranged horizontally by suitable variation in the lengths of the supports 10. The heating system has functioned satisfactorily and water of condensation has not collected to any appreciable extent in the heating circuits or 50 headers.

The last pipe sections 3, 3' of the outlet headers B, B' are threaded into flanged fittings 17, 17' which are riveted to the shell 1 of the tank, the bores of the fittings being also tapped from the outer side to receive outlet or return pipes 18, 18'.

As illustrated in Fig. 7, the flanged fittings to which the outlet headers are connected may 60 be secured to the bottom wall of the tank instead of the side wall, as shown in Fig. 3. This arrangement, and also that of the special angle fitting 19, Fig. 8, permits the bottom headers to be arranged somewhat closer to the 65 bottom of the tank. When the angle fitting 19

is employed, the steam outlet pipes 18, 18' may be tapped into the vertical or horizontal portion of the fitting. As shown in Fig. 8, the pipe 18 for outlet header B is tapped into the base of the fitting 19, while the pipe 18' for header B' is tapped into the side of the corresponding fitting 19'.

It will be apparent that the invention is not limited to the use of any particular number of heating units as the heating pipes of additional units could be located at the same level as the illustrated heating pipes 8, 8'. While the invention is particularly useful in the heating of tanks having flat bottoms it may be applied as well to tanks having convex or 80 concave bottoms.

It will be obvious that various changes may be made in the parts, their relative size, shape and relation without departing from the spirit of the invention as set forth in the following claims.

I claim:

1. In a heating system, an inlet header, an outlet header positioned at a level below said inlet header, said headers each comprising a plurality of aligned pipe sections, and pipe fittings to which the pipe sections of both headers are connected, said fittings each having chambers forming parts of the respective headers and adapted to receive an outflow and return heating pipe, respectively.

2. In a tank heating system, an inlet header, an outlet header below said inlet header, a fitting mechanically connecting and having chambers communicating with the respective headers, the walls of said chambers having tapped openings at substantially the same level for receiving outflow and return heating pipes, wherein the chamber communicating with the inlet header is located within the outlet header chamber, and the tapped opening of said first chamber is of less diameter than and coaxial with the tapped opening of the outlet header chamber.

3. In a tank heating system, vertically aligned inlet and outlet headers each comprising a plurality of pipe sections, and a series of duplex cross fittings cooperating with the pipe sections to form the said headers and to mechanically connect the said headers to each other, each of said duplex cross fittings having chambers communicating with the respective headers, and the walls of said chambers having tapped openings for receiving pairs of outflow and return pipes, respectively.

4. The invention as set forth in claim 3, wherein the outflow chamber of each fitting is surrounded by the return flow chamber thereof, and the tapped openings of said outflow chamber are of less diameter than and coaxial with the tapped openings of said return flow chamber, whereby the outflow and return pipes may be located at the same level.

5. In a tank heating system, a pair of inlet

headers and outlet headers, the outlet headers being in vertical alinement with the respective inlet headers and the corresponding headers of each pair being in horizontal alinement, a plurality of outflow and return heating pipes associated with the respective inlet and outlet headers, said heating pipes all lying substantially in a horizontal plane which passes between said inlet headers and 10 said outlet headers.

6. In a tank heating system, a plurality of horizontally alined inlet headers, an outlet header beneath each inlet header, means for supplying a heating fluid to each of said inlet 15 headers, each inlet header and its associated outlet header comprising a plurality of pipe sections arranged in two vertically spaced groups and duplex cross fittings connecting the pipe sections of each group to form the 20 said headers, said duplex cross fittings each having an outflow and return chamber communicating with the respective associated headers, the walls of said chambers having tapped openings at the same level, and a 25 closed heating circuit connected between the tapped openings of each cross fitting and comprising pipes located at the same level.

7. The invention as set forth in claim 6, wherein each inlet header and its associated 30 outlet header are spaced apart to permit the pipes of heating circuits associated with another pair of headers to pass between the same.

8. In a tank heating system, a plurality of 35 pipe sections arranged in two vertically spaced groups, the sections of each group

being located in substantially a single horizontal plane, a plurality of fittings connected to the pipe sections of both groups and co-operating therewith to form a pair of headers, 40 means for introducing a heating medium into the upper header, means for connecting the lower header to a return flow system, each of said fittings including an outflow and return chambers communicating with the respective 45 headers, the chamber opening into the upper header being enclosed by the chamber opening into the lower header, and a closed heating circuit extending from each side of said fittings, each of said heating circuits comprising a return flow pipe having a closed outer end and having an inner end communicating with the return flow chamber of its associated fitting, and an open-ended outflow pipe communicating with the outflow chamber of the said associated fitting, said outflow pipe being arranged within and spaced from the walls of said return flow pipe.

9. In a tank heating system, a duplex cross fitting comprising walls defining a pair of 50 parallel spaced passages therethrough, the walls adjacent the ends of said passages being threaded to receive header pipes, walls defining chambers extending from each of said passages towards the other passage and 55 one of said chambers lying within the other chamber, the walls of said chambers being provided with axially alined tapped openings for receiving the ends of a heating circuit.

In testimony whereof, I affix my signature.
JESSE C. COOK.
